Primary Examiner — Stacia Cadmus(74) *Attorney, Agent, or Firm* — Abelman, Frayne & Schwab(57) **CLAIM**

The ornamental design for a tire valve cap, as shown and described.

DESCRIPTION

FIG. 1 is a top perspective view of a tire valve cap showing our new design;

FIG. 2 is a top plan view thereof;

FIG. 3 is a side elevational view thereof, all other side views being the same thereof;

FIG. 4 is a bottom plan view thereof; and,

FIG. 5 is a bottom perspective view thereof.

The broken lines showing structural features are included for the purpose of illustrating non-claimed subject matter and form no part of the claimed design.
